(57) **CLAIM**

The ornamental design for a guide member for a dental drill, as shown and described.

DESCRIPTION

FIG. 1 is a front view of the guide member for a dental drill.
FIG. 2 is a top view thereof.

FIG. 3 is a bottom view thereof; and,

FIG. 4 is a reference view showing that claimed article is used in combination with the dental drill.

If present, dotted lines shown in the accompanying drawings are intended to illustrate environmental features not necessarily intended to be a part of the claimed drawing in the figures in which they appear.
